UNITED STATES PATENT OFFICE.

GROVER C. ROYSE, OF OGDEN, UTAH.

CONVERTIBLE BUILT-IN HOT-AIR FURNACE.

Application filed January 25, 1924. Serial No. 688,474.

This invention relates to furnaces of the type where the actual combustion takes place in or near the room to be heated. While the furnace is illustrated as being near the room 5 to be heated and such is the preferred location sight must not be lost of the fact that due to the more perfect circulation obtained, one or several rooms somewhat removed from the location of the furnace may be heated by 10 the device with perfect satisfaction. The primary object of the present invention consists in the provision of a convertible built-in hot air furnace which can be used as an open grate or by the addition of a one-piece 15 front can be used as an ordinary hot air furnace. Other objects of the present invention relate to the specific details of construction and various combinations of the parts of the furnace as called for in the claims.

20 In the drawings,—

Fig. 1 is a front elevation of a structure wherein the parts are assembled in the form of a furnace.

Fig. 2 is a front elevation with the structure converted into an open grate.

Fig. 3 is a view similar to Fig. 2 but showing the device in use as a grate.

Fig. 4 is a horizontal section through the air passage in the heating chamber.

30 Fig. 5 is a vertical section through the water pan box.

Fig. 6 is an elevation of the slotted damper control disk.

The furnace as will be seen from Figs. 1 35 and 2 does not differ materially in general appearance from well known types, having a cast metal sectional front, the upper section 10 of which is removably secured to the furnace frame 11 by any desired quick detachable means such for example as the locking pins 12. The usual hinged fuel door 13 is centrally positioned on the furnace front 40 preferably just below the hot blast draft 14 which leads to a hot blast pipe 15 of the 45 usual and well known type having for its purpose the delivery of the air over the fire which is built on the grate 16.

Just below the removable upper section 50 front 10 there is a permanent front section or bottom draft plate having at either side bottom drafts 17 and in the center a slot 18 for access to the handle 19 of the grate cleaner 20. A pair of ash drop doors 21 is

provided beneath the grate, these doors controlling the passageway to an ash pit 22, the 55 clean-out door 23 of which is preferably to the rear as shown, there being a solid wall 24 between the ash pit and the rotatable dampers 25 which control the passage of air through the pipes 27 and 28, these pipes 60 leading the cold air around the fire box to the heating chamber 30. The dampers 25 are located at the lower end of pipes 27 as shown in Fig. 2.

In the drawings, I have illustrated the 65 pipes 27 and 28 as being at the back and sides of the combustion chamber, but I may omit either the side pipes or the back pipe 27 under certain circumstances. The side pipes are numbered 28 in the drawings, and 70 the back pipe 27, which is preferably a large casting may extend over the entire back of the combustion chamber in which case it will have a plurality of rounded inwardly directed projections 32 to increase the heated 75 area of the air passage. The side pipes 28 are placed one on either side of the combustion chamber and each discharges against a small central vertical baffle 33 in the center of the heating chamber 30. The horizontal 80 floor 34 preferably is open at its back or rear as at 35 so that the cold air led up through the pipes 28 must move downwardly at the rear of the heating chamber 30 passing through the opening 35 and into the portion 37 leading at the front to the vertical hot air passage 38 which in turn merges into the diagonal passageway 39 and the tortuous 85 passageway 40 formed by the baffles 41 on alternate walls of the flue 42. The passageway 38 is integral with the walls of heating chamber 30 whereas the passageways 39 and 40 as well as the horizontal passageway 44 90 are formed of the bricks of the chimney and consequently are well insulated by any of the compounds in general use. The wall radiator 45 may be of the usual type and is preferably rather high up in the room as this is found to give the best diffusion of the 95 warm air.

100 The dampers 25 which consist of ported plates adapted to be rotated with respect to one another to open or close the ports, are controlled from the panel 51 by means of the handle 52 which carries a sprocket wheel 53 105 over which runs a chain 54 passing through

pipes 55 to the sprocket wheel 56 on the right hand damper 25 and by a second sprocket chain 58 to the sprocket wheel of the left hand damper 25. On the opposite side of the furnace front is a panel 60 similar to the panel 51, for the sake of symmetry the handle 61 of which is secured to the front of the water pan box or chamber 63, allowing access to the water pan 64 which is preferably arranged so as to project somewhat into the passageways 28.

The damper 70 is hinged as at 71 and carries a bail 72 which is engaged by the slot 73 of the disk or operating plate 74 carried by the rod 75 which also carries the operating handle 76 preferably placed just below the mantel 77. As will be seen from Fig. 6 the slot 73 in the damper operating plate is in the form of a spiral so that very close adjustment of the damper 70 may be had. The grate front 78 is detachably secured to the frame in the same manner as the furnace front.

What I claim is:

25 1. A convertible built-in hot air furnace having a fire box, a grate in the bottom of said fire box, a heating chamber at the top of said fire box, a removable front closing the entire front of the fire box, a stationary 30 built-in furnace frame to which said removable front is detachably secured, a tortuous passageway conducting air to said heating chamber, and a second tortuous passageway located in the flue for conveying the heated 35 air from the heating chamber to the space to be heated.

2. In a convertible built-in hot air furnace, a fire box, a heating chamber above the fire box, a furnace frame, a removable front detachably secured to the furnace frame, a plurality of dampers beneath the hearth of the furnace, and a plurality of passageways, leading from said dampers to the heating chamber, a damper above said heating chamber, and a tortuous passageway above said damper for conveying the heated air from the heating chamber to the space to be heated.

3. In a built-in hot air furnace adapted to be converted into an open grate, a fire box, 50 a sectional front for said fire box one section being permanent and the other section being removable, said permanent section having air supply openings for the fire box whereby the structure may be used as a grate 55 when the removable section is removed and said removable section having a fuel supply opening therein to permit the structure to be used as a furnace when said removable section is secured in place in the structure, a heating chamber located above said fire box, 60 a damper above said heating chamber, and means for raising and lowering said damper.

4. In a convertible built-in hot air furnace, a fire box, a damper located below said fire 65 box and at each side thereof, a heating cham-

ber above said fire box, an air passageway connecting each of said dampers with said heating chamber, and a single vertical baffle within said heating chamber against which each of said passageways discharges.

70

5. In a convertible built-in hot air furnace, a fire box, a heating chamber located above said fire box, said heating chamber consisting of a cast member having a horizontal floor dividing the chamber into an upper 75 and lower portion, said floor having openings therein at front and back, a plurality of passageways discharging into the upper portion of said chamber, a central baffle on said floor against which each of said passageways 80 discharge and a vertical passageway in front of the chamber for discharging the heated air received from the lower portion of the chamber.

6. In a convertible built-in hot air furnace, a fire box, a grate therein, an air conveying and heating chamber at the rear of the fire box and having bulging portions extending into the fire box above said grate, means for conveying air to said chamber, a second 90 heating chamber, a partition in said second chamber forming upper and lower chambers, the lower portion communicating with said rear chamber, a second cold air supply communicating with the second chamber above 95 said partition, said partition functioning to thoroughly commingle the two supplies of air and means for conveying the heated air from said second heating chamber to the space to be heated.

100

7. A convertible built-in hot air furnace characterized by the provision of a heating chamber above the fire, rear and side pipes leading to said chamber, said rear pipe being so proportioned in cross section with respect to the total cross section of the side pipes as to distribute equally the incoming air and means within said chamber for uniformly distributing the air supplied through the several side pipes with the air supplied 105 through the rear pipe.

8. A built-in hot air furnace adapted to be converted into an open grate, characterized by the provision of a heating chamber above the fire, means for conveying air to 115 said chamber, a removable section in the furnace front for closing the fire box, said removable section having a fuel charging opening therein whereby the structure may be used as a furnace when said removable section is secured in place, and a hot air blast pipe carried by said removable front section from the structure as a unit with said removable section.

120

9. In a convertible built-in hot air furnace, a fire box, a heating chamber located above said fire box, said heating chamber consisting of a cast member having a horizontal floor dividing the chamber into an upper and lower portion, said floor having 125

130

openings therein at front and back, a plurality of passageways discharging into the upper portion of said chamber, a central baffle on said floor against which each of said passageways discharge and a vertical passageway in front of the chamber for discharging the heated air received from the lower portion of the chamber, the bottom of said heat-

ing chamber facing the fire being concave downwardly whereby the air discharged from the upper part of the chamber follows around the outer sides of the lower part when it gets full effect of the heated gases as they rise from the fire and pass into the smoke flue. 10

GROVER C. ROYSE.
